BODY FOR MOTORCYCLE RADIO CADDY

Manuel D. Masterson, 413 Stedman Place,
Monrovia, Calif. 91016

Filed Feb. 24, 1975, Ser. No. 552,159

Term of patent 14 years

Int. Cl. D12—II

U.S. Cl. D12—114

FIG. 1 is a perspective view of a body for motorcycle radio caddy, showing my new design;

FIG. 2 is a top plan view thereof;

FIG. 3 is an end elevational view thereof of the end opposite to that shown in FIG. 1;

FIG. 4 is a rear elevational view thereof; and

FIG. 5 is a bottom plan view thereof.

I claim:

The ornamental design for a body for motorcycle radio caddy, as shown.
